US0D1023809S

(12) **United States Design Patent** (10) Patent No.: **US D1,023,809 S**
(45) Date of Patent: ** Apr. 23, 2024

(54) **WATCH DIAL**

(71) Applicant: **Cartier International AG**, Steinhausen (CH)

(72) Inventor: **Sophie Valzan**, Paris (FR)

(**) Term: **15 Years**

(21) Appl. No.: **35/517,510**

(22) Filed: **Mar. 10, 2023**

(80) **Hague Agreement Data**

Int. Filing Date: **Mar. 10, 2023**

Int. Reg. No.: **DM/227872**

Int. Reg. Date: **Mar. 10, 2023**

Int. Reg. Pub. Date: **Jun. 16, 2023**
